US00D870033S

(12) **United States Design Patent** (10) **Patent No.:** **US D870,033 S**
Varatharajah et al. (45) **Date of Patent:** **** Dec. 17, 2019**

(54) **BATTERY CASE**(71) Applicant: **CPS Technology Holdings LLC**, New York, NY (US)(72) Inventors: **Arunraj Varatharajah**, Menomonee Falls, WI (US); **Dale B. Trester**, Waukesha, WI (US)(73) Assignee: **CPS Technology Holdings LLC**, New York, NY (US)(**) Term: **15 Years**(21) Appl. No.: **29/648,893**(22) Filed: **May 24, 2018****Related U.S. Application Data**

(62) Division of application No. 29/592,243, filed on Jan. 27, 2017, now Pat. No. Des. 830,965.

(51) **LOC (12) Cl.** ..... **13-02**(52) **U.S. Cl.**USPC ..... **D13/103**(58) **Field of Classification Search**USPC D13/102–108, 110, 118–119, 184

Primary Examiner — Jennifer Rivard*Assistant Examiner* — Alison M Ofstun(74) *Attorney, Agent, or Firm* — Boardman & Clark LLP(57) **CLAIM**

The ornamental design for a battery case, as shown and described.

DESCRIPTION

FIG. 1 is an isometric view of a battery case showing our new design;

FIG. 2 is a front view of the battery case shown in FIG. 1; FIG. 3 is a rear view of the battery case shown in FIG. 1; FIG. 4 is a right side view of the battery case shown in FIG. 1;

FIG. 5 is a left side view of the battery case shown in FIG. 1;

FIG. 6 is a top view of the battery case shown in FIG. 1; and, FIG. 7 is a bottom view of the battery case shown in FIG. 1.

The broken lines are shown for the purpose of illustrating portions of the article which form no part of the claimed design.

1 Claim, 7 Drawing Sheets# US D870,033 S
